TRUSS

Moris Portnow, New York, N. Y.

Application December 28, 1940, Serial No. 372,061

2 Claims. (Cl. 128—106)

This invention relates to mechanical appliances for the treatment of rupture or hernia, and more particularly to appliances commonly referred to as trusses as used by individuals for the alleviation of rupture or hernia.

Broadly, the present invention has reference to trusses used in the treatment of double rupture and trusses used for the treatment of simple rupture.

Trusses for the treatment of double rupture generally comprise two spaced apart rupture pads mounted upon a supporting shield or base. In the case of trusses now in common use, this base or shield is made either of metal or of soft, pliable rubber. The former is obviously extremely uncomfortable, especially when the patient bends or sits, as the metal edges will tend to press against the body, and the latter is impractical, since the pliability of the base will tend to defeat the purpose for which the truss is intended.

With this in mind, it is the principal object of the present invention to provide a truss, which will supply the necessary stiffness, and yet be sufficiently pliable to be comfortable under all conditions.

A further aim of this invention lies in the provision of a truss of this character, the pad or pads of which are mounted upon a pliable base of novel construction, the base having a thicker and a thinner cross-section to assure the maximum of comfort to the wearer under all positions of the body.

A further feature of the present invention is the provision of a truss having a novel form of pad construction, which will prevent the pad from slipping, once it has been secured in its proper place.

A still further aim of the present invention resides in providing a truss of this character with a novel strap construction for retaining it about the body of the user, to the end that, in its application the patient may find the maximum of comfort under all body positions.

Yet another advantage of the present invention lies in the provision of a truss of this character, the several parts of which are so constructed as to make the truss as flat as possible, so as to prevent bulging when it is worn, and to make it as inconspicuous as possible, when it is applied to the body of a patient.

These and other meritorious aims and advantages, which will become more fully apparent as the description hereof proceeds, are accomplished by the novel construction of parts, hereinafter described and illustrated in the accompanying

drawing, forming a material component of this disclosure, and in which:

Figure 1 is a view of an embodiment of the invention, applied to the body of a person.

Figure 2 is a front elevational view, parts being broken away.

Figure 3 is a rear elevational view of the device, showing one form of pad and parts of the retaining straps.

Figure 4 is a sectional view, the section being taken on line 4—4 of Figure 2.

Referring in greater detail to the drawing, the numeral 10 designates in general a plate or base of pliable material such as rubber, upon which are mounted a pair of spaced cushion pads 11 and 12. The construction of the plate or base 10 is such that, throughout its length, the upper portion 13, comprising substantially one-half of the area of the plate, is thinner in cross-section, than the lower part 14. At the limit of the area of greater thickness and the beginning of the area of lesser thickness there is formed a line of demarcation 15.

Riveted as at 25 or otherwise secured to the outer face of the upper and lower portions of plate 10 are hook members 16 and 16'.

For retaining the device around the body of a wearer, there is provided a strap 17 preferably made of elastic material.

The ends 20—20' of elastic member or strap 17 have removably attached thereto a pair of buckle members 22—22' having a central bar upon which a plurality of toothed prongs are movably mounted, each of the buckle members having one end thereof formed into substantially rectangular loops 19 which, when the device is in operative position, engage the hook members 16.

There also is provided a lower strap of suitable inelastic fabric, designated in the drawing by the numeral 18, the ends of which being provided with a pair of buckle members 22 and 22' of like construction as the buckle members above described. Slidably mounted on the lower strap 18 are a pair of loops 23, the lower ends of which are provided with buckle members 23'. Secured between pads 11 and 12 and hook members 16 and 16' respectively are a pair of vertical leg straps 24 of inelastic fabric, which are retained in position by screws 26.

In operation, when it is desired to apply the truss illustrated in Figures 1, 2, 3, 4 and 5 of the drawing to the body of a person the plate and pads attached thereto are positioned over the part of the body which is desired to be pro-

tected, causing the permanently attached leg straps 24 to assume their normal, downreaching position. One of the loops of a buckle of strap 17 is hooked onto hook member 19, and the belt is then secured about the body by engaging the other loop with hook member 16. Prior thereto the belt may be adjusted as to size in the conventional manner, by removing one of the buckles and securing it closer to or farther away from one of the ends, depending upon whether the belt is to be shortened or made longer.

One of the loops of the buckle of inelastic strap 18 is then hooked onto one of the lower hook members and, after an obvious adjustment as to size has been made, the other loop is hooked onto the other hook member. The leg straps 24 are then taken up between the legs and secured in the rear to buckles 23 in such manner as to produce a snug fit.

When the pad structure illustrated in Figure 5 is employed instead of that shown in Figure 4, it will be apparent that pressure of cushion pad 12a against the rupture will force the pad inwardly of rim 12b, thus bringing the outer face of the rim into contact with the body of the user. Since that part of the rim which is intended to contact the body is not attached to the pad by cement or otherwise, but is retained about the pad by nature of the complementing contours of pad and rim, the rim will form a pocket when the pad is pressed inwardly, causing the pad to be retained firmly in its adjusted position, yet with the utmost comfort for the user.

It will be seen that there has been presented a truss, constructed for efficiency as well as for comfort in any position which the wearer's body may assume. Towards that end, the conventional metal plate has been eliminated, and in its stead a rubber plate 10 has been constructed in such manner, as to allow a certain amount of pliability without thereby sacrificing the effectiveness of the device. As will be seen in the drawing, plate 10 is not square in cross-section, but its upper and lower horizontal edges are curved inwardly to permit a freer movement of the abdomen above and below the area covered by the truss.

The construction of the straps too, tends to make this truss as comfortable as possible. To that end, belt 17 is made of elastic material. However, strap 18 is of inelastic fabric since to make it elastic would defeat the purpose for which a truss is intended.

Further modifications become apparent by an inspection of the disclosure and still others will become apparent through use.

Thus it will be seen that I have illustrated and described the best known embodiment of my invention, but it is to be understood that this disclosure is intended to be illustrative and descriptive thereof, and not restrictive or limitative to the exact construction shown, since I reserve for myself the right to make minor changes in the construction of the truss within the scope of the appended claims, without departure from the spirit of this invention.

Having thus described the invention, what is claimed as new and desired to secure by Letters Patent, is:

1. A truss comprising a pliable plate, a pair of cushion pads secured thereto, said plate comprising an upper longitudinal area and a lower longitudinal area, both of said areas being of substantially equal size, said upper area being thinner than said lower area, a line of demarcation throughout the length of said plate at the juncture of said area of greater thickness and said area of lesser thickness, a pair of hook members riveted to said upper area, a pair of hook members riveted to said lower area, a pair of leg straps retained by said last named hook members, an elastic strap having buckles at each end, said buckles being formed with loops for engagement with said first named hook members, an inelastic strap having a buckle at each end, said buckles formed into loops for engagement with said last named hook members, slidably means on said inelastic strap for removably retaining said leg straps in operative position, and means for adjusting said elastic and inelastic straps around the body.

2. A truss comprising a pliable plate, a cushion pad secured thereto, said plate divided horizontally into an upper part and a lower part of substantially equal size, said lower part being thicker in cross-section than said upper part, a horizontal line of demarcation throughout the length of said plate at the juncture of said parts, a pair of hook members riveted to said upper part, a pair of hook members riveted to said lower part, a pair of leg straps retained by said last named hook members, an elastic strap having buckles at each end, said buckles formed with means for engagement with said first named hook members, an inelastic strap having a buckle at each end, said buckles formed with means for engagement with said last named hook members, means on said inelastic strap for removably retaining said leg straps in operative position, and means for adjusting said elastic and inelastic straps around the body.

MORIS PORTNOW.
